UNITED STATES PATENT OFFICE.

ANDREW P. PRESTON, OF PORTSMOUTH, NEW HAMPSHIRE.

DESIGN FOR A BOTTLE.

SPECIFICATION forming part of Design No. 24,655, dated September 3, 1895.

Application filed July 5, 1894. Serial No. 516,690. Term of patent 14 years.

To all whom it may concern:

Be it known that I, ANDREW P. PRESTON, a citizen of the United States, residing in Portsmouth, in the county of Rockingham and State 5 of New Hampshire, have invented and produced a new and original Design for Bottles, of which the following is a specification, reference being had to the accompanying drawings.

The characteristic feature of my design consists of a bottle having, in appearance to the eye, two plain upright faces of nearly equal width, separated by a fluted configuration at nearly right angles to the two upright surfaces.

15 Figure 1 is an elevation of the bottle. Fig. 2 is a cross-section thereof on line xx .

In Fig. 1, which is an elevation of a bottle, showing my design, A is the square prismatic

body of the bottle, above which is the cylindrical neck B, which is in turn surmounted 20 by the cylindrical tip C. The neck B is of slightly smaller diameter than the body A, and is ornamented by beading, which, as shown, is arranged as a spiral around the neck. The tip C is of still smaller diameter and is 25 perfectly plain.

What I claim is—

The design for a bottle herein shown and described.

In witness whereof I have hereunto set my 30 hand.

ANDREW P. PRESTON.

Witnesses:

GEO. A. HOLMES,
E. H. GILMAN.
